UNITED STATES PATENT OFFICE.

JOSEPH A. GROEBLI, OF NEW YORK, N. Y., ASSIGNOR TO KURSHEEDT MANUFACTURING COMPANY, OF NEW YORK, N. Y.

EMBROIDERING-MACHINE.

No. 902,814.

Specification of Letters Patent.

Patented Nov. 3, 1908.

Application filed October 28, 1901. Serial No. 80,252.

To all whom it may concern:

Be it known that I, JOSEPH A. GROEBLI, a citizen of the United States, residing at the borough of Manhattan, city, county, and State of New York, have invented certain new and useful Improvements in Embroidering-Machines, of which the following is a specification.

My invention relates to embroidering machines and has special reference to improving the construction of embroidering machines having scallop mechanism.

In U. S. Letters Patent No. 607,848 granted on the 26th day of July, 1898, to the Kursheedt Manufacturing Company as my assignee, I have shown an embroidering machine provided with automatic scallop mechanism governed and controlled by a jacquard or pattern mechanism of the general type shown in U. S. Letters Patent No. 528,632 granted on the 6th day of November, 1894, to the Kursheedt Manufacturing Company as my assignee.

By my present invention I seek to produce an improved construction of scallop mechanism of a different type from that shown in the U. S. Letters Patent No. 607,848 aforesaid and to further improve the machine shown in the said Letters Patent.

I will now describe one form of machine in which my present invention is embodied and will point out the essential features of my present invention in the claims at the end of this specification, without, however, limiting myself to the construction shown, but desiring to include all structures of this character which, within the limitations imposed by the state of the art, are equivalent structures. I may say that this invention finds its chief embodiment in machines wherein the scallop mechanism requires to be positioned for use and normally is not in operative position.

In the accompanying drawings, which illustrate one embodiment of my invention, Figure I is a side elevation of one end of an embroidering machine showing a sufficient number of parts to illustrate my present invention; it being understood that many essential parts of the embroidering machine and its controlling jacquard or pattern mechanism are omitted from the illustration in order to fully and adequately present the invention without undue complication. Fig. II is a side elevation of the

parts shown in Fig. I. Figs. III and IV are detail views of the locking pawl which serves at pre-determined times to connect the scallop mechanism to its driving shaft which imparts motion thereto; Figs. V, VI, VII and VIII are detail views showing the parts which connect the scallop apparatus positioning bar with its advancing and restoring lever in several successive positions.

In the drawing 1 indicates the frame of the embroidering machine, and 2 the jacquard or pattern mechanism for controlling the functions thereof which is preferably of the type shown in U. S. Letters Patent No. 528,632 above mentioned.

3—3 indicate the levers for operating one of the take-up bars of the embroidering machine, or other suitable functioning mechanism, which levers may be connected by link connections 4, provided with a pin 5 co-operating with a cam 6 on a shaft 7. The take-up bars may be normally given their usual motion by any usual well-understood operating means not shown, and the cam 6 when the scallop attachment is in action serves to vary or modify this motion in harmony with the action of the scallop mechanism.

8 indicates one set of the scallop mechanism, which is given a swinging movement from a vertical rock-shaft 9 to which movement is imparted by cam 10 on the shaft 7 in any desired manner. The shaft 7 is provided with a gear 11 which receives its motion from a gear 12, which receives its motion from a pinion 13 carried upon a sleeve 14, loosely carried upon a shaft 15 which is continuously driven from the main shaft of the machine.

A notched disk 16 is secured to the shaft 15, see Figs. I, III and IV. The sleeve 14 is provided with an arm 17 to which a dog 18 is pivoted having a tail 19 receiving the thrust of a leaf-spring 20 secured to the sleeve 14. The nose of the dog 18 is adapted to engage in the notch 21 of the disk 16 and the tail 19 is adapted to rest normally when the scallop apparatus is out of action against an arm or abutment 22 carried by the operating rod 23 of the scallop mechanism so that the nose of the dog 18 is normally held in the position shown in Fig. IV when the scallop mechanism is not in operation.

The operating rod 23 of the scallop mech-

anism is provided with a pin 24 which is adapted to rest in a notch of a cam 25 fixed on the shaft 7 when the scallop mechanism is out of action. The operating rod 23 is provided with one or more racks 26—27, the rack 26 coöperating with a toothed sector 28 which serves to move the upper scallop hooks when they are in action and rack 27 coöperating with a sector 29 which serves to operate the lower row of scallop hooks and to raise the operating rod 23 to lift the pin from the notch in the cam 25. The operating rod 23 is connected by a suitable link 30 with one arm of a bell crank lever 31, whose other arm 32 is connected by rod 33 with an arm 34 pivoted at 35 and provided with an arm 36 having journaled thereon a gear 37 and sheave 38. The gear 37 is denuded of a sufficient number of teeth at a suitable point in its periphery, say at 37^a, so that when this portion of the gear 37 is reached by the pinion 40 with which it is meshed, at times, the pinion can rotate idly and the movement of the gear 37 will be discontinued. The reason for this will be apparent later. The pinion 40 is carried upon a suitable counter shaft 41 which is provided with a pulley 42 imparting motion by a belt 43 to the main shaft 44 of the embroidery machine.

The counter shaft 41 is provided with a cone pulley 45 which is connected by a belt 46 with a cone pulley 47 carried upon a suitably driven shaft 48. The shaft 48 imparts motion to the shaft 41 by which the main shaft 44 of the embroidery machine is driven. A belt shifter 49 slides upon a suitable guide, and is adapted to embrace the belt 46 which transmits motion from the pulley 47 to the pulley 45. A cord 50 attached to the belt shifter is connected at one end to the sheave 38 and passes around the sheaves 51—52, being provided with a weight 60, which weight serves to restore the parts to their normal position.

A latch lever 53 actuated by a spring 59 is pivoted at 54 and is provided with a toe 55 adapted to coöperate with the abutments 56—57 to lock the gear 37 in the position into which it has been moved. The object and function of the parts just described is to change the rate of motion of the embroidery machine when the scallop mechanism is thrown into action. The detailed operation thereof is as follows: The bell crank 32 being swung, pushes upon the setting rod 33, which permits the spring 58 to draw the short end 36 of the lever 34 downward, thereby meshing the gear 37 with the pinion 40 and causing the said gear to be rotated by the pinion 40. The rotation of the gear 37 will cause the sheave 38 to pull upon the cord 50 to cause the belt shifter 49 to be moved laterally to shift the belt 46 upon the cone pulleys, thereby changing the rate of

motion of the embroidery machine to conform to the requirements of the festoon functions.

When the blank space 37^a in the gear 37 reaches the pinion 40, rotation of the gear 70 will cease and the abutments 56—57 will have been brought into position to coöperate with the locking lever 53 whose toe end 55 is forced upward by its spring 59. When the festoon operation ceases the rod 33 is pulled, thereby raising the gear 37, which being thus released from the locking lever 53 is permitted to rotate in a reverse direction under the influence of the weight 60 so that the parts are thus automatically restored to a normal position. It will likewise be observed that the belt shifting will occur immediately upon the operation of the link 33 so that the other operations of the embroidery machine may take place immediately.

Having described the operation of the scallop apparatus and the speed controlling mechanism, I will now proceed to describe the means whereby the functions of all these mechanisms are initiated. The sector 29 is carried upon a shaft 61 provided with an arm 62 connected to a scallop apparatus positioning bar 63. The scallop apparatus positioning bar, which will hereinafter be referred to as the positioning bar, is connected to a lifter or mover 64 operated from the jacquard or pattern mechanism. This lifter or mover 64^a is preferably under the control of the jacquard pins which in Letters Patent No. 528,632 above referred to are identified as serving to initiate functions and effects in the embroidery machine other than moving the fabric frame. This jacquard lifter or mover serves to lift or move the end of the positioning bar at predetermined times in order to bring the edge 64 thereof into position to be acted upon by a setting and restoring lever 67 receiving its movement from a cam on the shaft 44 of the embroidery machine. This lever 67 which is pivoted at 68 has a swinging movement imparted to it by the said cam and serves when the free end of the positioning bar is raised into its path of movement to thrust the said positioning bar forward, thereby raising the rod 23 to position the scallop attachment for operation, disengage it from the notch in its operating cam 25, and to set the speed regulating or determining apparatus in motion.

In Figs. V, VI, VII and VIII, I have shown in detail the mechanism for initially moving the positioning bar 63 holding it in its active position, and restoring it to its initial position.

In Figs. VI, VII, and VIII I have omitted the arm 65; this arm 65 operates to reset the connecting piece when the parts have been restored to their initial positions, and also to move the connecting piece the first step of its movement.

The arm 65 is pivoted at 69 and is provided with a cam *c* and with an arm 70 which is provided with a bowl engaging in the cam 66. A bracket 71 forming a stationary part of the machine frame is provided with a locking piece 72 having a hook *i* with an exterior cam surface 73, and with a retaining piece *g*. The positioning bar 63 is provided with a locking projection *h*, which is adapted to lock behind the hook *i* of the locking piece 72. Pivotally carried by the free end of the positioning bar 63 is a connecting piece 75 which is herein shown as being of a triangular shape *e* at one side of its pivot 76 and provided with a lug *f*. On the other side of its pivot the connecting piece is provided with a finger *j* and a hooked end of peculiar shape, the recess of the hooked end being provided with an inclined face *k* at one side and an inclined face *l* at the other side. The parts just described serve to support and retain the end of the positioning bar when it has been lifted by the jacquard, and the lever 67 has operated to push it forward and the scallop mechanism has come into operation, and to effect with the aid of the lever 67 the restoration of the positioning bar to its initial position.

The operation of the construction just described is as follows: When the jacquard lifter has raised the free end of the positioning bar 63 and has brought the surface 64 of the said bar 63 within the range of action of the arm 67, the said arm imparts to the said bar a forward motion to effect the positioning of the scallop apparatus. A secondary effect of this movement is to bring the triangular piece *e* into the path of movement of the cam *c*, which depresses same so that the net result of this movement will be to bring the lug *f* behind the retaining piece *g* of the bracket 71. The parts are so positioned in order to hold the positioning bar in its set position, and to prevent it from following the return movement. This is the position shown in Fig. VI wherein the bar 63 has been slightly raised and moved in the direction of the arrow in Fig. V. As the first motion of the scallop device is taken the bar 63 is moved slightly forward by the scallop device, and allowed to drop slightly by the jacquard, so that the locking lug *h* drops behind the hook *i* and is there retained or supported while the scallop apparatus is making its motions; it being understood that the finger *j* comes against the cam 73 to further swing the connecting piece. When the scallop apparatus has finished its motions the jacquard lifts the end of the bar 63 and the lever 67 again comes into action. This lever 67 swinging forward strikes against the face *k*, thereby further tilting the connecting piece 75 and entering the triangular portion 77 of the lever 67 into the recess in the connecting piece 75. The re-

turn swing of the lever 67 in the direction of the arrow in Fig. VIII is effective to draw the positioning bar 63 back to its initial position as the jacquard holds the end of bar 63 up so that the lug *h* will clear the hook *i* on the return movement, and as the jacquard apparatus permits the end of bar 63 to drop the connecting piece 75 will be restored to its normal position which is shown in Fig. II by the end *a* of arm 65 striking against it.

The operation of the apparatus as a whole will now be described. The embroidering machine in normally operating imparts a normal throw to the take-up bar operating levers 3, and to the other parts of the machine. Now, at a predetermined period the jacquard apparatus comes into action to effect the positioning of the scallop apparatus. To do so it raises upon the lifter 64, thereby raising the positioning bar 63 into position to be moved forward by the vibrating arm 67, which forward movement of the positioning bar is effective to raise the operating bar 23, thereby positioning the festoon mechanism, lifting the pin 24 out of the slot in the cam 25, and by removing the rest or abutment 22 from the tail 19 of the lever 18 (see Figs. II, III and IV) couples the scallop shaft 16 whereby the proper cams will come into action and effect a proper movement of the scallop apparatus. At the same time the rod 30 rising permits the spring 58 to draw downward upon the arm 36 thereby throwing the speed adjusting or determining device in action, and as the action of the said speed determining apparatus is brought about by positive movements, the embroidering machine will go into action at the proper moment and at a proper rate of speed. When the sewing functions of the embroidering machine are being performed the take-up mechanism of course operates in harmony with the needle movement, but as the timing of the needle movement is changed when the scallop mechanism goes into action the needle movement is differently timed and the take-up movement varies accordingly, the timing of the entire mechanism being changed by the change of speed.

Having described my invention what I claim and desire to secure by Letters Patent is:

1. An embroidering machine including in its structure a scallop apparatus and its operating means, and independent automatic positioning means for positioning the scallop apparatus for operation, operating independently of the scallop apparatus operating means.

2. An embroidering machine, including in its structure a scallop apparatus means for operating the same and a common automatic means for positioning the scallop apparatus for action and initiating the operation of the said scallop apparatus.

3. An embroidering organism, comprising the combination with an embroidering machine provided with scallop mechanism, operating mechanism therefor, and independently operating positioning mechanism for said scallop mechanism of a jacquard device for initiating the operation of the positioning mechanism.
4. An embroidering organism comprising in its structure an embroidering machine provided with scallop mechanism, operating mechanism therefor and independently operating positioning mechanism for the scallop mechanism, an actuating device for said positioning mechanism, and automatic means for controlling the operation of the actuating device.
5. In an embroidering organism the combination with an embroidering machine, including scallop mechanism, operating mechanism therefor, independently operating positioning mechanism for the said scallop mechanism, and actuating mechanism for the said positioning mechanism, of pattern mechanism controlling the inter-action of the positioning mechanism and its actuating mechanism.
6. In an embroidering machine the combination of a scallop mechanism with pattern controlled mechanism for determining its periods of action, a take-up mechanism operated in time with the scallop mechanism, the timing of the operation of said take-up mechanism being also determined by the pattern mechanism substantially as described.
7. In an embroidering machine including a pattern mechanism and, an operating element of the embroidering machine, with means for positioning the said operating element for action controlled from the pattern mechanism and mechanism for determining the rate of speed at which such individual operating element shall operate, comprising a variable speed device operating normally to drive the embroidering machine at a normal speed and comprising means for varying the speed at predetermined times embodying positively acting engageable and disengageable gears for varying the ratio of transmission between elements of the variable speed device and means for initiating the operation of the said gear mechanism from the positioning mechanism comprising positively actuated devices for insuring immediate positive action of said gear mechanism.
8. In an embroidering mechanism the combination of a scallop mechanism, operating mechanism therefor, independently operating means for positioning the said scallop mechanism and speed regulating mechanism controlled by the positioning of the scallop mechanism.
9. In an embroidering machine the combination of a scallop mechanism, operating mechanism therefor, a jacquard or pattern mechanism and independent automatically operating means controlled by the jacquard or pattern mechanism for positioning the scallop mechanism for action and withdrawing it out of operative position.
10. In an embroidering mechanism the combination of a scallop mechanism, operating means therefor, means for positioning the said scallop mechanism and a pattern mechanism for controlling the operation of the positioning mechanism, whereby the positioning mechanism is set and returned to an initial position through the intervention of pattern mechanism independently of the operation of the scallop mechanism.
11. In an embroidering machine the combination of a scallop mechanism, means for positioning the said scallop mechanism adapted to position the said scallop mechanism and to permit it to remain positioned during the normal operation of the scallop mechanism and for withdrawing the scallop mechanism out of operative position and pattern mechanism for controlling the said positioning and withdrawing means.
12. An embroidering machine including an operating element thereof, means for bringing said element into action and means for changing the speed of the embroidering machine to effect the proper timing of the operations of the said element, comprising in its structure a variable speed device, means for gradually changing the ratio of transmission between the elements of the variable speed device so as to effect a gradual change in the speed of the embroidering machine at predetermined times, comprising engageable and disengageable gears and pattern mechanism for controlling the operating element and the engageable and disengageable gears.
13. An embroidering machine comprising in its structure a scallop mechanism, a pattern mechanism for setting the scallop mechanism in action, and means for operating said scallop mechanism comprising a variable speed device, engageable and disengageable gears adapted to operate the speed device so as to effect a gradual change in the ratio of the speed device and effect a gradual change of speed in the embroidering machine and means operated by said pattern mechanism for causing said gears to engage and disengage to effect said change of speed.
14. In an embroidering organism, the combination of embroidering apparatus including an operating element thereof having positioning means for positioning the said element for operation and withdrawing the said element from operation at predetermined times—a variable speed device normally driving the embroidering machine at a normal rate of speed and including means

- for effecting a gradual change in the ratio of transmission between elements of the variable speed device embodying positively acting engageable and disengageable gears with 5 means for driving one of said gears independently, and pattern mechanism for controlling the positioning means and the intermeshing of the engageable and disengageable gears, so as to gradually change the 10 speed of the machine to accommodate the timing of the operating element.
15. In an embroidering organism the combination of embroidering devices, a variable speed connection including cone pulleys ar- 15 ranged to drive the embroidering devices at a normal speed, engageable and disengageable gears for varying the ratio of transmission between the cone pulleys, and means for causing said gears to mesh and change the 20 speed ratio of said pulleys and pattern mech- 20 anism adapted to operate said last means.
16. In an embroidering organism the combination of an operating element of an em- 25 broidering machine and positioning means for positioning the same for operation, a variable speed connection for the embroidering machine, including cone pulleys and 25 positively acting engageable and disengageable gears operating to vary the ratio of 30 transmission between the cone pulleys, and a connection between the said gears and the 30
- positioning mechanism whereby when the said operating element is positioned for operation a change of speed of the embroidering machine will be thereby effected. 35
17. In an embroidering organism the combination of an operating element of an em- 40 broidering machine, means for positioning said element for operation and for withdraw- 40 ing the same to its inoperative position and pattern controlled means adapted to re- 45 lease said positioning means when said operating element has been positioned and to reengage said positioning means to return said operating member to its inoperative po- 45 sition.
18. The combination in an embroidering organism of an operating element of an em- 50 broidering machine having means for effecting its normal operation, means for setting or positioning said element for action and for withdrawing said element from the set position, said means being independent of the operating portions of the said mech- 55 anism, and pattern mechanism for controlling the action of the said setting and with- drawing mechanism.
